Term of patent 7 years

(Cl. D33—6)

To all whom it may concern:

Be it known that I, Isaac Lazarus, a citizen of England, residing at London, England, have invented a new, original, and ornamental Design for Dressing Table, of which the following is a specification, reference being had to the accompanying drawing, forming a part hereof.

Fig. 1 is a lefthand front perspective view of a dressing table, showing my new design.

Fig. 2 is a perspective view from the rear.

Fig. 3 is a side elevation.

I claim:

The ornamental design for a dressing table, as shown.

ISAAC LAZARUS.
